UNITED STATES PATENT OFFICE.

FREDERICK W. CHILD, OF GREENWICH, CONNECTICUT.

ENGINE-COUNTER.

SPECIFICATION forming part of Letters Patent No. 351,164, dated October 19, 1886.

Application filed December 7, 1885. Serial No. 184,968. (No model.)

To all whom it may concern:

Be it known that I, FREDERICK W. CHILD, of Greenwich, in the county of Fairfield and State of Connecticut, have invented certain new and useful Improvements in Engine-Counters, of which the following is a specification.

This invention relates to an improved device for counting the rotations of the driving shafts or strokes of engines, pumps, and other machinery in a reliable and effective manner; and the invention consists of the combination of a train of registering gear-wheels, a primary spur-wheel, an oscillating escapement operated by the engine or machine, and a spring by which said spur-wheel is intermittently moved, said spring being automatically wound up by a pawl-and-ratchet device operated by a lever connected to the oscillating escapement directly or by the engine or machine.

In the accompanying drawings, Figure 1 represents a front elevation of my improved counter connected to a steam-engine; and Figs. 2 and 3 are respectively a side elevation and a front elevation, with parts removed, of the counter, drawn on a larger scale.

Similar letters of reference indicate corresponding parts.

Referring to the drawings, A represents an intermeshing train of gear-wheels and transmitting-pinions, the shafts of which are provided with pointers that move along face-dials, as customary in counting-registers for steam-engine pumps and other machinery. Motion is imparted to the train of registering-wheels A by a primary spur-wheel, B, to the shaft B' of which is keyed a pinion, b, which meshes with the first gear-wheel of the train of gear-wheels A. A second pinion, d, is keyed to the shaft B' of the spur-wheel B in front of the same, said gear-wheel meshing with a barrel or drum, C, having a circumferential gear-wheel, d'. In the barrel C is arranged a coiled spring, D, which is attached at its outer end to the barrel and at its inner end to the shaft C' of the barrel C, which shaft turns in bearings of the casing A of the counter, as shown in Fig. 2. A ratchet-wheel, e, is keyed to the shaft C' of the spring-barrel and engaged by a spring-pawl, e', and check-pawl e'', the pawl e' being pivoted to an oscillating rod, E, that is hung by an eye or sleeve to the shaft C' of the

spring-barrel, and connected by a link, E', with the lever-arm F' of an escapement, F, that is fulcrumed to the casing A' of the counter below the spur-wheel B in such a relative position to the spur-wheel B that the teeth of the escapement F engage alternately the teeth of the spur-wheel B. The lower end of the lever-arm F' of the escapement F is connected in any suitable manner to the piston-rod, crank-shaft, 60 or other rotary or reciprocating part, the rotations or strokes of which have to be counted.

The oscillating rod E, instead of being connected to the lever-arm F', may be directly connected like the lever-arm F' with the piston-rod, crank-shaft, or other actuating part.

At each oscillation of the escapement the spur-wheel B, which is impelled by the action of the coil-spring D, and the gear-wheel d' and pinion d, move forward for the distance of one tooth, so 70 that the regular and reliable action of the spur-wheel B is obtained, whether the oscillations imparted to the escapement by the strokes of the engine or other machine are longer or shorter. No skipping of one of the teeth of 75 the spur-wheels by longer strokes is possible, as the spring moves the spur-wheel at the moment when it is released by the escapement. By the lever-connection of the escapement F or moving part of the engine or other machine 80 with the pawl-and-ratchet mechanism of the spring-barrel the spring of the same is automatically wound up again at every second stroke, so that the same is always in a condition to move the spur-wheel B and keep it in 85 engagement with the teeth of the escapement.

The oscillating lever-rod E is made thin enough to be flexible, so that in case the spring is wound up to its full extent the rod E will "give" sufficiently to the motion of the escapement-lever without breaking the spring, as shown in dotted lines in Fig. 3. This is an essential point, as otherwise the spring D, ratchet-wheel e, or transmitting gear-wheels d d' would be liable to be broken and the regular 95 operation of the counter jeopardized. By actuating the train of registering-wheels by a spur-wheel and escapement oscillated by the engine or machine and impelling the spur-wheel by a spring which is wound up at every second 100 stroke of the engine or other machine, a counting-register is obtained that requires no setting

or winding up by the attendant, and that performs its work in a reliable and accurate manner without being liable to get out of order or fail to record the strokes, whatever be the length 5 of the same.

Having thus described my invention, I claim as new and desire to secure by Letters Patent—

1. The combination, with the piston-rod of an engine, of a train of registering gear-wheels, 10 a primary spur-wheel, an oscillating escapement actuated by said piston-rod, the strokes of which are to be counted, a spiral spring impelling said spur-wheel, and means, substantially as described, whereby said spring is automatically wound up by the escapement or 15 directly by the engine or machine, substantially as set forth.
2. The combination, with the piston-rod of

an engine, of a train of registering gear-wheels, a primary spur-wheel, an oscillating escapement actuated by said piston-rod, the strokes of which are to be counted, a coil-spring, a barrel for said spring, a gear-wheel and pinion for transmitting the power of the spring to the spur-wheel, a ratchet-wheel applied to the 20 shaft of the spring-barrel, and an oscillating rod and pawl, by which the spring is intermittently wound up again, substantially as set forth.

In testimony that I claim the foregoing as 30 my invention I have signed my name in presence of two subscribing witnesses.

FREDERICK W. CHILD.
